UNITED STATES PATENT OFFICE.

ALEXANDER J. PEET, OF BROOKLYN, NEW YORK.

BOILER.

SPECIFICATION forming part of Letters Patent No. 761,394, dated May 31, 1904.

Application filed December 21, 1900. Serial No. 40,641. (No model.)

To all whom it may concern:

Be it known that I, ALEXANDER J. PEET, a citizen of the United States, and a resident of the borough of Brooklyn, in the county of Kings and State of New York, have invented certain new and useful Improvements in Boilers, of which the following is a specification.

This invention relates to means for the economical production of steam. Its object is the production of boilers which will be compact in form, with large steaming capacity, light in weight, and accessible for repairs.

Figure 1 represents a vertical section of the boiler on the line xx of Fig. 2. Fig. 2 shows a fragmentary top view and a section on the line yy of Fig. 1. Fig. 3 is a fragmentary side view of the boiler, taken on a plane at right angles to the section shown in Fig. 1. Fig. 4 represents a view of two adjacent steam-coils as seen when looking in a direction of the line xx of Fig. 2. Fig. 5 shows a top view of the hollow stand of the boiler. Fig. 6 represents a fragmentary section, on an enlarged scale, through one end of one of the coils on the line tt of Fig. 2.

The boiler consists of the central column A, with the T B, which contains the separating plate b, perforated with the holes b'. To the T are secured the pipes C, closed at their ends with the plugs D. The T with pipes C constitute the steam-dome. The central column A is carried on the hollow stand E, to which is secured the ring-plate bottom F. Steam-coils H are screwed into the central column by means of the fittings h, the said fittings being first screwed on the ends of the coils and then screwed into the central column, the threads on the external and internal surfaces of the fittings being right and left to each other.

The convolutions of the coils H are oblong in plan view and enlarge in diameter from their inner to their outer ends, and in vertical elevation they each take the shape of a helix. The coils are secured to the central column so as to interlace each other, as shown in Figs. 2 and 4, the pitch of the coils allowing one coil to be interposed between the members of the next adjacent coil. By this disposition any of the coils can easily be re-

moved, and a great many coils can be put in a small volume of space. To vary the capacity of any boiler, the lengths of the coils as measured on horizontal planes are increased or decreased, avoiding thereby the necessity of more than one circular row of coils. If more than one row of concentric coils are introduced, they would not be accessible for repairs.

The coils are surrounded by the circular shell G, which is capped with the smoke connection I. To the inner face of the shell G is secured a non-conducting lining J. An outer casing L encircles the shell G and a non-conducting filling K is interposed between them.

In the plugs D are tapped pipes M, on which is loosely supported the dry pipe N, the latter being perforated with numerous holes n for the passage of the steam from the steam-dome into said dry pipe and by which it is conducted into the pipes M.

In the hollow stand E is cast the boss e, which contains two openings entirely through the same. In the lower end of one opening the oil-pipe O is secured, and into the opposite end of said opening the coil P is fastened, running from there in a spiral up the central column A, and returning to the inside of the hollow stand E at p. The boss e contains a second opening for the water-inlet pipe Y. A secondary boss e' is cast with e, which contains an opening extending from the outside of the stand E to the inside of the same, and into the opening of this secondary boss the oil-outlet pipe R is secured. Legs e'' extend from the stand E, and the braces U are fastened to the said legs for securing the boiler in place.

Surrounding the legs of the stand E, and on the top face of the leg f of the ring bottom plate F is placed the burner T, which contains numerous openings t'. It is provided with a mixing-chamber T', into the end of which is placed a needle-valve S. The pipe R extends from the inside of the hollow stand E to the needle-valve.

The leg f of the ring bottom plate is perforated with holes f² and slots f³. On the top of said leg there is placed an annular ring 100

F' with holes f⁴ and projecting pins f⁵, which constitutes the damper.

To the bottom of the stand E is fastened the reservoir V for alcohol or a similar fluid 5 to start the burner.

A water-column X, with water-glass x', is secured in place, with the piping x³ extending from the steam-dome C, and the piping x² running to a fitting y' in the water-inlet pipe Y.

10 To generate steam, the boiler is first charged with water through the pipe Y, after which oil is forced through the pipe O and into the coil P. Then a charge of alcohol in the reservoir is lighted to heat and vaporize the oil in the coil P. The oil finds its way into the pipe R to enter the mixing-chamber T' through the valve S, where it mixes with the air drawn into the mixing-chamber, and the mixture is forced through the holes t' in the burner, 15 where it is lighted and heats the water in the steam-coils H. By means of the damper the amount of air admitted to secure perfect combustion is regulated. The steam leaves the coils at their upper ends, and enters the central 20 column A under the separating-plate b of the T B, and passes through the holes b' to enter the steam-dome, from which it enters the dry pipe N, and is finally led into the pipes M, which convey it to any desired point. The products 25 of combustion pass up about the coils and enter the smoke connection I, by means of which they are carried away.

Having described my invention, I desire to secure by United States Letters Patent and 30 claim—

35 1. A boiler comprising a central water-column, helical coils secured thereto at their top and bottom ends, the coils interlocking with each other, a stand fastened to the bottom end 40 of said central water-column, a fuel-coil entering from said stand and into the central water-column, a shell encircling the steam-coils, a smoke connection capping the said shell, a bottom plate with damper secured to 45 the stand, and a burner above said bottom plate.

2. A boiler comprising a central water-col-

umn, spiral coils secured thereto at their top and bottom ends, the coils interlocking with each other, a hollow stand fastened to the 50 bottom end of the water-column, a fuel-coil extending from the said stand and into the central water-column, a shell encircling the steam-coils, a smoke connection capping the said casing, a bottom plate with damper secured to the stand, a burner encircling the stand and supported on said bottom plate, a valve secured to the burner, an oil-supply pipe extending from the hollow stand to the 55 valve.

3. A boiler comprising a central water-column, interlocking steam-coils secured to the water-column, the convolutions of which are helical in elevation and, in plan view, increase in diameter from their inner to their outer 60 ends, a hollow stand fastened to the bottom end of the water-column, a fuel-coil running from a boss extending through the stand and returning to the inside of the same, an oil-supply pipe leading to the oil-coil, a water-supply pipe connected to an opening running through the stand, a fuel-outlet pipe extending from inside of the said stand, a reservoir under the stand, a shell surrounding the steam-coils, a smoke connection capping the shell, 65 a T with perforated plate secured to the central water-column, pipes fastened to the T, plugs secured into the ends of the said pipes, steam-pipes tapped into the plugs, a perforated dry pipe connecting the inner ends 70 of the steam-pipes, a bottom plate with damper secured to the stand, a burner encircling the stand, a mixing-chamber fastened to the burner, a needle-valve supported in the mixing-chamber, a fuel-pipe extending from the 75 stand to the needle-valve.

Signed at New York, in the county of New York and State of New York, this 17th day December, A. D. 1900.

ALEXANDER J. PEET.
